UNITED STATES PATENT OFFICE.

OLIVER HEWLETT HICKS, OF CHICAGO, ILLINOIS, ASSIGNOR TO THE MORGAN ENVELOPE COMPANY, OF SPRINGFIELD, MASSACHUSETTS.

BUNDLE OF TOILET OR WRAPPING PAPER.

SPECIFICATION forming part of Letters Patent No. 425,033, dated April 8, 1890.

Original application filed July 17, 1885, Serial No. 171,894. Divided and this application filed January 31, 1889. Serial No. 298,260. (No specimens.)

To all whom it may concern:

Be it known that I, OLIVER HEWLETT HICKS, of Chicago, in the county of Cook and State of Illinois, have invented certain new and useful Improvements in Bundles of Toilet or Wrapping Paper; and I do hereby declare the following to be a full, clear, and exact description of the same, reference being had to the accompanying drawings, forming a part of this specification, and to the letters of reference marked thereon.

My invention has for its object to furnish toilet or wrapping paper in a form convenient for use without wastage; and it consists in an improved form of bundle or package, which I will now proceed to describe.

In the drawings, Figure 1 represents a perspective view of a bundle of paper constructed in accordance with my invention. Fig. 2 is a sectional view of the same.

Similar letters of reference in both the figures indicate the same parts.

In forming my improved bundles or packages I wind one or more continuous lengths of paper upon a comparatively large-sized mandrel until a continuous band of paper A is formed of an internal diameter preferably not less than about twice the thickness of the band at any given point. This band, after its formation, I then weaken, preferably by cutting or slitting it from both sides nearly to the middle, as shown at B, and then applying a wire or other stay—such as W—by passing it through the slits or cuts and around the middle portion C, for the purpose of holding all the layers or convolutions of paper in their original relative positions—that is to say, with the lines of cutting or weakness all in the same plane, and for the further object of providing means by which to suspend the package. To remove a sheet or section from the band, it is only necessary to grasp the depending free end and pull it slightly laterally, when it will separate on the line of weakness produced by the incisions or slits, the new free end thus formed dropping down automatically, or left in position to be easily pulled down into position to be grasped for the next operation.

It is obvious that the upper portion of the 50 wire W forms a loop or eye, by which the package can be conveniently hung up or suspended, when desired.

I am aware that toilet-paper has heretofore been put up in the form of continuous lengths, 55 perforated at regular intervals and wound into rolls, which are then supported upon central cores; but it is obvious that in such a construction the perforated and weakened portions of the lengths do not, when wound 60 into roll form, come into line or register, and that, consequently, the advantages which I obtain by weakening the paper after its formation into the band and applying the stay thereto are not obtainable. 65

Having thus described my invention, what I claim as new is—

1. A toilet or wrapping paper roll or band having all of its incisions or lines of weakness in the same plane and provided with a stay 70 applied thereto, substantially as described, to keep the said incisions or lines of weakness in the same plane.

2. A toilet or wrapping paper roll or band having all of its incisions or lines of weakness 75 in the same plane and provided with a stay passed through said incisions or lines of weakness and secured therein, substantially as set forth.

3. A toilet or wrapping paper roll or band 80 having all of its incisions or lines of weakness in the same plane, combined with a stay passed through said incisions and secured therein, the outer end of said stay having an eye by which the roll or band may be suspended, substantially as described.

4. A toilet or wrapping paper roll or band having all of its incisions or lines of weakness in the same plane, combined with a stay 90 passed through said incisions and having its inner portion engaging the inner part of the roll or band, substantially as set forth.

OLIVER HEWLETT HICKS.
